NONREFILLABLE BOTTLE

John J. McDonald, West View, Pa.

Application October 5, 1934, Serial No. 746,999

2 Claims. (Cl. 215—22)

This invention relates to new and useful improvements in non-refillable bottles, and it is among the objects thereof to provide a valve arrangement in the neck of a bottle which will 5 permit emptying the contents from the bottle in its tilted position while preventing refilling of the bottle in any position and which shall embody means for preventing flow of the liquid contents when the bottle is in a horizontal position.

These and other objects of the invention will become more apparent from a consideration of the accompanying drawings constituting a part hereof in which like reference characters designate like parts and in which:

Fig. 1 is a fragmentary cross-section of a bottle neck and valve mechanism embodying the principles of this invention;

Fig. 2 a similar view of a slightly modified form of the device shown in Fig. 1;

Fig. 3 a fragmentary cross-sectional view of a bottle valve and neck of Fig. 1 with its axes disposed horizontally;

Fig. 4 a similar view of the bottle neck and valve in a tilted position for pouring;

Figs. 5 and 6 a cross-section and plan view respectively of the valve cap;

Figs. 7 and 8 plan and cross-sectional views respectively of the valve body;

Fig. 9 an elevational view of a ball member;

Figs. 10 and 11 plan and cross-sectional views respectively of the valve;

Figs. 12 and 13 plan and cross-sectional views respectively of an end member for the valve body;

Figs. 14 and 15 a plan and cross-sectional view respectively of a cork liner;

Figs. 16 and 17 a cross-section and elevational view respectively of a modified form of cap member; and

Fig. 18 a fragmentary view in elevation of a bottle neck embodying the valve of Fig. 2 of the drawings.

In the drawings the numeral 1 designates a bottle neck of somewhat larger diameter than the neck of a conventional bottle having a cylindrical inner wall 2 slightly enlarged near the end as indicated by the reference numeral 3, the outer wall of the neck being provided with a bead 4 of conventional form and a thread 5 for receiving a cap or closure 6.

The bottle neck for the different forms of valve elements of Figs. 1 and 2 is identical. Disposed within the neck 1 is a valve housing 7 more clearly illustrated in Figs. 7 and 8, the

exterior of which is provided with a constricted portion 8 for receiving a cork strip 9, Figs. 14 and 15, which functions as a seal between the valve body and bottle neck. The cork liner 9 may be grooved at 10 to receive a tab with printed indicia thereon to designate the brand, origin or serial number of the liquid contents or shipment or to designate the manufacturer of the bottle or both, as shown in Fig. 18.

The interior of the valve body 7 is hollow and grooved as shown at 11 and ribs 12 are provided as tracks for the ball member 13 to permit the flow of fluid around the ball through a plurality of flow passages 14, four of such passages being shown in Fig. 7. The upper end of the valve body 7 is provided with lugs 15 and a projection 16 that cooperate with the lugs 17 and wall 18 of an end cap generally designated by the numeral 19 shown in Figs. 5 and 6, the surfaces 18 and 16 being spaced to provide a flow passage 20 and the lugs 15 and 17 prevent seating of the end cap on the top of the valve body 7 at any portion excepting on lugs 15 and 17. The end cap 19 is provided with a central hemispherical portion 20 to divert the flow of the fluid leaving passages 14 and as will be seen in Fig. 8 the top of the valve body 7 is concave at its midportion to prevent the projection 20 from contacting the end of the valve body. The end cap 19 is fused to the valve body 7 at the lug portions only to firmly secure the two parts into an integral member.

A hollow plug 21, Figs. 12 and 13, is adapted to be inserted in the bottom end of the valve body 7 as shown in Fig. 1, and a flat disk valve 22, Figs. 10 and 11, is adapted to rest on the member 21 to control the flow of liquid through the central passage 23. Valve 22 is shaped as shown in Fig. 10 so that the lugs 24 contact the inner wall 11 of the valve body to center the valve on the flow passage 23 when in its closed position. The cutout periphery of the valve between the lugs 24 provides maximum flow of the fluid past the valve disk when the latter is unseated.

The parts are assembled in the manner shown in Fig. 1 and the valve body 7, end cap 19, ball member 13, disk 22 and the hollow end closure 21 are preferably made of porcelain although, obviously, the ball and valve members could be made of glass or other materials.

The valve element is placed in the neck of the bottle 1 after the bottle has been filled, the parts having previously been assembled as shown in Fig. 18.

Fig. 1, the valve body being cemented to the inner wall 2 of the bottle neck.

In the position shown in Fig. 1 the ball 13 rests upon the valve 22 to seal the contents of the bottle, at the same time permitting venting of any gas pressure generated in the bottle chamber. When it is desired to pour liquid from the bottle, it is tilted as shown in Fig. 4 in which position the ball 13 abuts the inner projection 13a of the valve body and the valve disk 22 drops away from its seat to permit the fluid to flow from passage 23 around the ball 13 through the passages formed by the ribs 12 and out through passages 14 into the end cap from which it flows in a divergent path between the space formed by the walls 16 and 18 through the openings formed by the spacing lugs 15 and 17. When the bottle is brought to its upright position, the weight of the ball will again seal valve 22 and if the bottle is disposed in a horizontal position as shown in Fig. 3, the curvature of the ribs 12 and the inner wall 11 of the valve body will force the ball against the disk 22 as shown in Fig. 3, thus preventing the flow of fluid from the mouth of the bottle. While the force of the fluid within the bottle is sufficient to displace the valve 22 and ball 13 in the horizontal position of the bottle, the atmospheric pressure on the open side of the valve will hold the valve closed as the displacement of any liquid from the interior of the bottle will reduce the pressure on the inner side of the valve. This is an important feature of the bottle valve. In the modification shown in Figs. 2 and 18 the end cap 19 is provided with a flange 19a that engages the top of the bottle neck, the flange 19a being provided with slots 19b to permit flow of the liquid therefrom.

A suitable closure cap 6 may be provided for the form of end cap shown in Figs. 2 and 18, this being desirable to prevent exposure of the mouth of the bottle and valve to the atmosphere.

While many forms of non-refillable bottles have been heretofore proposed, it is evident from the foregoing description of this invention that a valve structure made in accordance therewith not only provides for the easy pouring of the contents of the bottle and prevents refilling of the bottle but also prevents spilling of the contents when the bottle is placed in a horizontal

position. Also, with the arrangement shown the valve cannot be removed from the bottle neck without destroying the entire bottle. The valve parts, when made of porcelain, can be economically produced in commercial quantities so that the use of the valve will not materially increase the cost of the contents. 5

Although one embodiment of the invention has been herein illustrated and described, it will be evident to those skilled in the art that modifications may be made in the details of construction without departing from the principles herein set forth. 10

I claim:

1. In a non-refillable bottle the combination with a bottle neck of a valve therefor, said valve consisting of a main body portion extending substantially the full length of the neck having a hollow interior of curved and ribbed walls, an end cap adapted to be fused to the top of the valve body to form flow passages leading to the hollow interior of the valve, a hollow end member for the bottom of the valve having a restricted flow passage of lesser diameter than the inner wall of the valve, a flat disk seated on said end member, and a ball freely movable on the interior of the valve body, the curved wall of the valve body extending beyond the seat of the disk valve whereby the ball is forced against the valve in any position of the bottle between a perpendicular and horizontal axis. 20 25

2. In a non-refillable bottle the combination with a bottle neck having a cylindrical inner wall of a valve adapted to extend substantially the full length of said neck, said valve comprising a hollow body portion having a curved inner wall forming a track for a ball and having flow passages extending to the upper end thereof, an end cap fused to the upper portion of the valve body having flow passages formed by the spacing of the cap with the end surfaces of the valve body, a valve seat with a constricted flow passage disposed in the lower end of the valve body, a valve disk disposed on said seat, a ball within the hollow interior of the valve body adapted to engage said valve, and a packing material disposed around the exterior of the valve body extending a portion of its length and yieldingly engaging the inner wall of the bottle neck. 30 35 40 45 50
